FINGER RING WITH A SLIDE CONNECTOR

Jules Braunstein, North Hollywood, Calif.

Application June 7, 1948, Serial No. 31,560

5 Claims. (Cl. 63—15)

1

This invention relates to a finger ring ensemble or set, and deals more particularly with novel and improved means for connecting two rings so that they do not relatively rotate while on the finger.

An object of the present invention is to provide separable connecting means for a ring ensemble that is slidably carried by one ring to have selected retracted and projected positions, whereby, in the retracted position, said means does not mar the beauty of the ring and in the projected position, said means effects firm yet separable connection with the other rings of the ensemble to hold said rings against relative rotation.

Another object of the invention is to provide a ring ensemble in which one ring is conventional and is known as a fishtail ring, and the other is formed to slidably carry a projectable connector that firmly yet separably engages an element or elements of the fishtail design to effect a non-rotational connection of the two rings.

The foregoing objects and other objects, features and advantages of the invention will appear from the following detailed description of preferred embodiments, the same having basis on the accompanying drawing in which:

Fig. 1 is a cross-sectional view of a ring ensemble according to the present invention.

Fig. 2 is an enlarged broken plan sectional view through one of said rings, the same being taken on the plane of line 3—3 of Fig. 1 and the ring-connecting element being shown retracted.

Fig. 3 is an enlarged plan sectional view through both rings of the ensemble as connected, the same being taken on line 3—3 of Fig. 1.

Fig. 4 is a fragmentary sectional view as taken on line 4—4 of Fig. 3.

Fig. 5 is a plan view of an alternate form of ring-connecting element.

The ring ensemble that is shown in the drawing comprises, generally, rings 10 and 11, and ring-connecting means 12.

The ring 10 may be variously formed. As shown, the same comprises a shank 13 for encircling the finger and a stone or gem setting box 14. Except as hereinafter described, ring 10 is connectional, the box 14 having the usual passage 15 for admitting light from the bottom to impinge on a stone or gem that is fitted to the setting box.

According to the present invention, the box 14 is provided with a slideway 16 that extends from side to side of the box adjacent to the bot-

tom, said slideway being defined by a lower wall 17, at the bottom, the main portion 18 of the box, at the top, and end walls 19. In practice, the slideway is filed or otherwise machined in the bottom of the box and then enclosed at the bottom by wall 17 which is soldered in place. The slideway may be provided in other feasible ways.

As herein contemplated, the inner faces of walls 19 are tapered as at 20, from the sides of the ring 10 toward the center thereof to meet at opposed detents 21. The slideway 16 is thus widest at the sides of the ring and restricted or narrowed at the center. Inasmuch as the depth of the slideway, top to bottom, is relatively small, the same being in the nature of .010", the beauty of the ring is in nowise marred, the ends of the slideway merely appearing as slits or grooves that are in keeping with other grooves usually formed in the box to enhance the appearance of the same.

While ring 11 may be formed in various ways the same is shown as a conventional fishtail ring on the shank 22 of which is mounted the fishtail elements 23 in any desired number. Said elements are connected as shown best in Fig. 4 and have a generally oval form to provide generally triangular spaces 24 between adjacent elements. These spaces are well suited to receive the ring-connecting means 12 which is formed to frictionally engage either opposite edges 25 of the central element 23, if the ring embodies an odd number of such elements, or adjacent edges 25 of adjacent elements, if the ring embodies an even number of such elements.

The ring-connecting means 12, as shown in Figs. 1—4, comprises a flat spring slide member 26 that is generally of U-shaped form and of a thickness to freely slide in slideway 16. Said member, as seen in Fig. 2, in its retracted position resides entirely within the slideway, no part of the same projecting beyond the sides of the setting box 14. Said member is formed with similar flexible leg portions 27 that are preferably integrally connected by a transverse portion 28, at one end, the opposite free ends 29 of the flexible leg portions 27 thereby being resilient and resiliently movable toward and from each other.

The outer edge of each leg portion 27 is provided with spaced seats or notches 30 and 31 for selective engagement with the detents 21. The opposed seats 30 are located at the approximate middle of the leg portions and when engaged with said detents, the member 26 is held centrally in the slideway as in Fig. 2. The opposed

seats 31 are located between the seats 30 and the bridged end of the member. By pushing on said bridged end 28 with any suitably sharp element, the slide member can be projected as in Figs. 1 and 3, the leg portions 27 merely flexing inward toward each other as the slide is pushed and the seats 31 then snapping into engagement with detents 21. It will be noted that the transverse bridge 28, while flexible to permit flexing of the leg portions, cannot flex up or down, being confined in the slideway. Hence the slide member cannot be pushed too far and can have only the projected position shown.

The free ends 29 of the leg portions may be suitably formed to frictionally engage either the opposite edges 25 of a fishtail element 23 of ring 11, substantially as shown, or adjacent edges of adjacent elements as above stated. Said frictional engagement may be increased by forming snap seats 32 in ends 29 either on the inner edges of said ends, on the outer edges, or both.

After the slide member has been projected, ring 11 is positioned thereagainst and a slight pressure on said ring will effectively connect the same to ring 10. The rings are thus held against relative rotation. It will be evident that separation of the rings is readily effected.

Instead of the flat spring member 26, the connecting means 12 can comprise a length of spring wire of suitable size having the U-shaped form desired and having the leg portions 27a, bridge connecting portion 28a, seats 30a and 31a, etc.

While the invention is shown with the detents in the box and the engaging seats in the slide, the same may be reversed if desired. The construction, however, when the ring is to mount a precious stone, should be such that member 26 does not unduly obstruct the passage of light to the stone from the bottom.

It will be evident that variations within the spirit and scope of the invention may be made within the scope of the appended claims. I therefore do not wish to restrict myself to the embodiments herein described.

I claim:

1. A finger ring formed with a transverse slideway extending from one side of the ring to the opposite side, a slide element in said slideway and movable from an inoperative retracted position entirely confined within the slideway to an operative projected position beyond one side of the ring, ring-engaging means on the projected portion of the slide element adapted to engage a separate finger ring when said slide element is in said operative position to hold said separate ring non-rotational relative to the ring having the slideway, and means provided in the slideway to engage and hold the slide element in both positions thereof, selectively.

2. A finger ring formed with a transverse slideway extending from one side of the ring to the opposite side, a slide element in said slideway and movable from an inoperative retracted position entirely confined within the slideway to an operative projected position beyond one side of the ring, two ring-engaging resilient free ends on the projected portion of the slide element and adapted to frictionally engage a separate finger ring when the slide is in said operative projected position to hold said separate ring non-rotational relative to the ring having the slideway, and means provided in the slideway to en-

gage and hold the slide element in both positions thereof, selectively.

3. A finger ring formed with a transverse slideway extending from one side of the ring to the opposite side, a slide element in said slideway and movable from an inoperative retracted position entirely confined within the slideway to an operative projected position beyond one side of the ring, said slideway having opposed detents, two pairs of opposed seats formed in the slide element and each pair of seats having engagement, selectively, with said opposed detents to hold the slide element when moved to retracted or projected position as desired, and ring-engaging means on the projected portion of the slide element adapted to engage a separate finger ring when said slide element is in said operative position to hold said separate ring non-rotational relative to the ring having the slideway.

4. A finger ring formed with a transverse slideway extending from one side of the ring to the opposite side, a slide element in said slideway and movable from an inoperative retracted position entirely confined within the slideway to an operative projected position beyond one side of the ring, said slideway having opposed detents, two pairs of opposed seats formed in the slide element and each pair of seats having engagement, selectively, with said opposed detents to hold the slide element when moved to retracted or projected position as desired, and two ring-engaging resilient free ends on the projected portion of the slide element and adapted to frictionally engage a separate finger ring when the slide is in said operative projected position to hold said separate ring non-rotational relative to the ring having the slideway.

5. A finger ring formed with a transverse slideway extending from one side of the ring to the opposite side, a resilient U-shaped slide element in said slideway and movable from an inoperative retracted position entirely confined within the slideway to an operative position with the free ends of the legs of said element projected beyond one side of the ring, said slideway having opposed detents, two pairs of opposed seats formed in the slide element and having engagement, selectively, with said opposed detents to hold the slide element when moved to retracted or projected position as desired, and two ring-engaging jaws on the projected portion of the slide element and adapted to frictionally engage a separate finger ring when the slide is in said operative position to hold said separate ring non-rotational relative to the ring having the slideway.
